UNITED STATES PATENT OFFICE.

WILLIAM MACDONALD, OF WINNIPEG, MANITOBA, CANADA.

CLOTHES-POUNDER.

1,078,739.

Specification of Letters Patent. Patented Nov. 18, 1913.

Application filed October 14, 1912. Serial No. 725,718.

To all whom it may concern:

Be it known that I, WILLIAM MACDONALD, a citizen of the United States of America, residing at the city of Winnipeg, in the Province of Manitoba and Dominion of Canada, having invented certain new and useful Improvements in Clothes-Pounders, do hereby declare that the following is a clear and exact description of the same.

10 My invention relates to laundry devices known as clothes pounders and has for its object the producing of an article of this kind more effective for the purpose designed than those previously in use, and one, the 15 parts of which may be readily reached for cleaning purposes.

I attain my purposes by the means illustrated in the accompanying drawings in which—

20 Figure 1 is a view of the under side of the pounder. Fig. 2 is a vertical sectional view on the line A. A. in Fig. 1. Fig. 3 is a view of the soap receptacle cover and the lower plate attached thereto.

25 Similar numerals refer to similar parts throughout the different views.

In Figs. 1 and 2, 3 is a conical body preferably of sheet metal, disposed about and rigidly attached to a tube 4, which passes 30 through the apex of the cone 3 and down for a distance thereinto, and which serves as a socket for the handle 5, which is shown with the upper end broken off. To the lower end of the tube 4 is secured a soap receptacle 35 6, which is surrounded by a partition or flange 7 designed to isolate the upper part of the cone 3 from the lower part thereof. This partition may be either joined to the soap receptacle 6 or to the tube 4 as may 40 appear most suitable, but in either case the joint is made water tight as is also that between the periphery of the diaphragm and the cone 3. The soap receptacle 6 connects with its cover 8 by means of interengageable 45 peripheral screw-threaded walls 9 with which each is provided. Surrounding the cover 8 and forming a part thereof, is the diaphragm 10, the periphery of which fits the cone 3, and which is drawn into and held 50 firmly in place in the cone by the screwing of the cover 8 upon the soap receptacle 6. Secured to the outer periphery of the cone 3 are a number of semi-conical conduits 11

which extend from near the lower end of the cone to points adjacent to the apex thereof, 55 and have communication with the interior of the cone 3 between the partitions 7 and 10 by the openings 13. The upper part of the soap receptacle 6 is furnished with openings 14 communicating with the interior of the cone, and the cover 8 is provided with openings 15 communicating with the outside.

In practice a cake of soap or other washing compound is placed in the receptacle 6, 65 and the cover 8 screwed into place, taking with it the diaphragm 10. As the diaphragms 7 and 10 are of unperforated material the space between them forms a chamber communication with which is only to 70 be had by means of the openings previously described. The pounder is operated by hand in connection with a tub containing clothes and water, and in a vertically reciprocal manner. As the pounder is pushed down 75 the water rushes up through the conduits 11, through the openings 13 into the chamber formed between the diaphragms 7 and 10, and into the receptacle 6 where it becomes saturated with the washing compound. 80 When the pounder is raised the saturated water is thereby caused to flow from the receptacle 6 out through the openings 15 in the cover 8. When the pounder is raised a partial vacuum is formed under 85 it, thus facilitating the discharge of the water through the receptacle 6, and compelling a circulation through the clothes contained in the tub.

It will be noted that the removal of the 90 cover 8 of the soap receptacle and with it the diaphragm 10, leaves the interior of the pounder all open for cleaning purposes.

I claim as my invention—

A clothes pounder comprising a conical 95 body or shell, a centrally disposed tube extending thereinto, a screw threaded soap receptacle at the end of said tube, a horizontally disposed imperforate partition above the soap receptacle dividing the interior of the cone into two parts, a cover for said soap receptacle, a circular flange surrounding and attached to said cover and extending to the wall of said cone, said cover being screw threaded for engagement with 100 the threads on said receptacle, whereby said 105

flange is held in peripheral contact with said shell, conduits extending upward from near the bottom of said conical shell, and communicating with the interior of said cone between the partition therein and the flange around said cover, and openings in said soap receptacle and the cover therefor, whereby uninterrupted circulation is per-

mitted through said conduits, the interior of said cone, said soap receptacle and said cover.

WILLIAM MACDONALD.
